Inventor:

Mayme K. Schinkal.

UNITED STATES PATENT OFFICE.

MAYME KOLB SCHINKAL, OF CINCINNATI, OHIO.

DESIGN FOR A MEDICINAL TABLET.

43,829.

Specification for Design.

Patented Apr. 8, 1913.

Application filed August 22, 1912. Serial No. 716,538. Term of patent 14 years.

To all whom it may concern:

Be it known that I, MAYME KOLB SCHINKAL, a citizen of the United States, residing at No. 213 West Ninth avenue, in the city of Cincinnati, county of Hamilton, and State of Ohio, have invented a new, original, and ornamental Design for a Medicinal Tablet, of which the following is a specification, reference being had to the accompanying drawing, forming part thereof.

The figure is a plan view of a tablet showing my new design.

I claim:

The ornamental design for a medicinal tablet as shown.

MAYME KOLB SCHINKAL.

Witnesses:

ALBERTA COREY,
R. C. WICKLIFFE.
